INSECTICIDE ATOMIZER

Hyman Richard Rich, Chicago, Ill., assignor to
West Disinfecting Company, Long Island City,
N. Y., a corporation of New York

Application July 31, 1947, Serial No. 764,974

2 Claims. (Cl. 299—86)

1

The present invention relates generally to atomizers, and more particularly to a spraying type of atomizer for atomizing a liquid insecticide and spreading it in a form of cloud or fog over a relatively large area. These insecticide atomizers have very widespread application to factories, warehouses, bakeries, kitchens and innumerable other situations where insect control is desired.

In order to be effective, where insect kill is desired, the liquid insecticide should be diffused into a veritable fog. My improved atomizer has been designed and constructed to disseminate a relatively dry mist of insect-killing droplets of extremely small size, about eight microns or so. As a result of this extremely fine atomization, no condensation is noticeable, at least the extremely small particles will not wet or condense on tables, walls, etc., or any other equipment with which they come in contact provided that the atomizer is in operation the proper length of time.

Another particular feature of my improved atomizer herein disclosed is an improved constant level feed arrangement which automatically maintains the liquid insecticide at a substantially constant level in the tank or liquid reservoir from which the aspirating nozzles draw the insecticide. This constant level control is obtained by supplying the insecticide through a supply pipe to the atomizer under a constantly acting pressure or gravity head, and utilizing a float controlled inlet valve associated with the atomizer for maintaining a substantially constant liquid level in the liquid reservoir of the atomizer. This feature avoids the labor of feeding the liquid reservoir by hand pouring from another container, and avoids the uncertainties and irregularities of such hand feeding. In some installations there may be a large number of these atomizing units, and in most instances they are disposed quite close to the ceiling of the room, from which it will be seen that it is quite a laborious task to hand feed a large number of these atomizer units. My improved automatically operating constant level control is also advantageous over prior types of feed systems which are manually turned on at intervals when it appears to the operator that the supply in the atomizer reservoirs may be getting low. This still leaves the supply of the liquid insecticide subject to human error and forgetfulness. Still further, such manually controlled feeding arrangements necessarily result in wide variations of liquid level in each reservoir, starting with a relatively high level immediately after each feed-

2

ing interval and then dropping down to a low level or no level at all after a series of spraying operations or after a relatively long spraying operation. Such wide variations of liquid level adversely affect the desired object of producing an extremely fine atomization for obtaining a relatively dry mist of extremely small droplets. When the device is subject to a wide range of liquid level, the aspirating nozzles from which the liquid is atomized lift the liquid through a relatively short head when the liquid level in the reservoir is high, and lift the liquid through a relatively large head when the liquid level in the reservoir is low. This variation of suction lift results in objectionable variations in the atomization of the liquid at the nozzle outlet. This objection is avoided by my improved atomizer characterized by a float controlled inlet valve which maintains a substantially constant level of the liquid insecticide in the reservoir.

In my improved atomizer I preferably employ approximately ten or twelve separate liquid nozzles, and I arrange each of these nozzles to draw liquid from the reservoir through its own individual feed tube, so that the accidental plugging or restriction of one liquid nozzle or its individual feed tube will not disturb the feed to the other nozzles nor the effective liquid level supplying the other nozzles.

30 The aspiration and atomization of the liquid insecticide at each liquid nozzle is effected by a high velocity jet of gas projected in predetermined aspirating relation to the liquid nozzle. This gas is usually compressed air, but where 35 that is not readily available it is also practicable to employ steam, carbon dioxide or any other suitable gas under pressure as the propellant and atomizing medium. This compressed air, steam or gas is fed to each atomizing unit 40 through a system of piping which is substantially parallel to the system of piping which supplies the liquid insecticide to the atomizing unit.

Another feature which I employ in my improved atomizer is a unit assembly arrangement 45 wherein each atomizer has a section of liquid supply pipe and a section of air supply pipe fixedly joined thereto in the unit assembly, so that each atomizer and its associated sections of liquid supply pipe and air supply pipe are shipped as a unit, delivered as a unit, and installed as a unit. This simplifies the handling and the installation problem and greatly reduces the number of connections which have to be made by the workman in the installation of the atomizer.

50 55 Other features, objects and advantages of the

invention will appear from the following detail description of certain preferred embodiments thereof. In the accompanying drawings illustrating such embodiment:

Figure 1 is a side elevational view of one preferred embodiment of my invention adapted for fixed installation;

Figure 2 is a transverse sectional view through the liquid reservoir showing the arrangement of the liquid aspirating nozzles and the air jet nozzles; and

Figure 3 is a detail view showing the float controlled inlet valve.

Referring first to Figure 1, the atomizer alone is designated 10, and comprises a liquid reservoir 11, preferably in the form of a casting composed of aluminum or one of the lighter non-corrosive alloys. As shown in Figure 2, the reservoir is of substantially cylindrical form except that along the upper portion it is formed with a flat deck wall 12 through which extend the liquid aspirating nozzles 13. Formed integral with the reservoir and extending longitudinally above the center of this top deck wall 12 is an air conduit or manifold 14 from which extends the air jet nozzles 15 in aspirating relation to the liquid atomizing nozzles 13. This air manifold 14 is integrally joined with the liquid reservoir through the vertical rib 16. The ends of the reservoir chamber 11 have relatively large openings 18 cored therein, which are adapted to be closed by removable end plates 19 secured to the reservoir casting by cap screws 21. The automatic float valve mechanism is inserted into the reservoir 11 through one of these end openings 18, as I shall presently describe. A top filler opening 24 is also provided in the shelf or deck level 12 of the reservoir, and this filler opening is normally closed by a removable filler plug 25 which screws into the opening. This filler opening provides for inspection purposes and also for manual filling under circumstances when the automatic float valve unit is not utilized or not functioning. The removable filler plug 25 is provided with a suitable atmospheric vent to maintain atmospheric pressure within the reservoir 11 above the liquid level.

As shown in Figure 2, each liquid nozzle 13 comprises a small bore tube 26 which is rigidly mounted in a threaded mounting sleeve or bushing 27 provided with a hexagonal head portion 28. The threaded bushing 27 screws down into a threaded hole 29 in the shelf or deck portion 12 of the reservoir. When screwed into place, the lower end of the tube 26 extends down substantially below the substantially constant liquid level maintained in the reservoir 11. I preferably insert a small sleeve in the lower end of the tube 26. This sleeve prevents any dirt particles entering the tube which might lodge at a higher level in the tube, and such sleeve can also be utilized for calibrating or metering purposes, if desired. If desired, the threaded mounting plug 27 can be screwed upwardly or downwardly in the hole 29, and different thicknesses of shims may be employed under the hexagonal head 28, if it should be desired to adjust the upper discharge end of the tube 26 to a predetermined point relative to the level of the air discharge stream occurring from the associated air jet nozzle 15.

Referring now to the construction and mounting of these air jet nozzles, the air manifold 14 is formed with a series of spaced bosses 31 projecting laterally from each side thereof at points corresponding to each of the liquid nozzles 13.

These bosses are angularly inclined at increasing angles each way from the central jet so as to give a wide angle of distribution covering almost the entire circular area around the insecticide atomizer. Each of these bosses 31 has an internally threaded passageway 32 opening into the interior of the air manifold. The air nozzle 15 comprises a threaded shank portion 33 and a hexagonal head portion 34, the threaded shank portion 33 being screwed into the threaded passageway 32. The discharge orifice of the air nozzle is disposed substantially on a line with the tip end of the fuel nozzle 13.

Referring now to the automatic float valve mechanism, the liquid insecticide is conducted to the atomizer unit through the supply tube 35 which has detachable coupling with an inlet fitting 36. This inlet fitting has a threaded stem portion 37 which passes through an aperture in one of the cover plates 19, being secured to this cover plate by nuts 39 screwing over the stem. A bracket extension 41 projecting from the inner end of the threaded stem carries a transverse pivot pin 42. This bracket extension is longitudinally slotted, and a lever 44 is mounted in this slot for pivotal movement around the pivot pin 42. The upper end of said lever is pivotally connected at 45 with a valve stem 46 which extends into the fitting or valve body 36 and carries an inlet valve 47 at its inner end adapted to close an inlet part 48. The lower end of the lever 44 has connection with an arm extending from one end of a relatively long cylindrical float 52. If desired, the connection between the lever 44 and arm 51 may be arranged for angular adjustment, as by providing a threaded hole 53 in the lever and utilizing a clamping screw which threads into this opening for frictionally clamping the lever and arm together in any desired angular setting. This adjustment enables the predetermined liquid level within the reservoir to be set at any desired point. The float 52 and the valve operating linkage 51 and 44 are so proportioned that they can be readily inserted into the reservoir through the end opening 18. This float controlled inlet valve is operative to maintain a substantially constant liquid level within the reservoir 11 between very close limits.

The insecticide supply tube 35 is connected with the outlet side of an insecticide strainer 55. This may be of conventional type comprising a fine mesh straining screen and also a glass bowl serving as a trap for removing sediment and any heavier liquids. The inlet side of this strainer is connected through any conventional pipe fittings 56 with the insecticide supply pipe or header section 58.

Referring now to the compressed air connection to the air manifold 14, both ends of this manifold have internally threaded bosses 61, and a nipple 62 extends from one of these bosses for connection with the outlet side of an air strainer 63. This strainer comprises a fine mesh screen for removing any dirt or foreign particles from the air stream which might plug any of the air jet nozzles 15. In addition, this strainer may also include a blow-off valve. The inlet side of this strainer has connection through conventional pipe fittings 65 with the air supply pipe or air header 66.

Referring now to the above described unit assembly arrangement wherein the atomizer 11, liquid strainer 55, air strainer 63, liquid header 58 and air header 66 are all assembled as a unit, transported as a unit, and installed as a unit,

it will be seen that the air and liquid headers are disposed in superposed relation directly above the center of the atomizer 11 and extending longitudinally thereof. The two headers or supply line sections 58 and 66 are coupled together in vertically spaced relation by double pipe clamps 71, 71. Each double clamp consists of two duplicate straps or stampings having semicircular bends 72 embracing opposite sides of the header pipes, and having flat end and intermediate portions 73 which are clamped together by bolts 74. A hanger bar 75 engages over the upper bolt 74 between the upper clamping ends 73, and carries a ceiling lag screw 76 at its upper end adapted to be screwed up into the ceiling of the room or other enclosure. In this manner, the entire unit assembly can be quickly and easily hung in place by merely screwing the lag screws 76 into the ceiling and then coupling these lag screws to the hanger bars 75 by the bolts 77.

The right hand end of the atomizer 11 is suspended from the adjacent hanger by screwing a short nipple 78 into the right hand threaded boss 61 of the air manifold and closing off this nipple by an end cap 79. A clamping band 81 is then clamped around the nipple 78 and is connected to the lower end of the adjacent hanger assembly by a bolt 82. The liquid and air supply headers 58 and 66 may be provided with conventional threaded ends for receiving standard couplings or unions, or the ends of these headers may be furnished with any desired coupling or union devices, for establishing ready connection with sections of pipe leading to other unit assemblies or to the sources of insecticide supply or air supply. Thus, it will be seen that the entire assembly shown in Figure 1 can be constructed, shipped, sold and installed as a single unit, so that it is only necessary to mount the lag screws 76 and establish appropriate pipe connections with the ends of the supply headers 58 and 66. Flat supporting feet 84 project laterally from the bottom of the reservoir 11 for supporting the assembly in upright position during shipment, storage and the like.

Instead of being stationarily mounted, my improved atomizer can be constructed and arranged for movement through the area to be sprayed. For example, my atomizer may be used for spraying the interiors of railroad passenger cars at the end of the run or at periodic intervals when the cars are being cleaned. For this type of service, my improved atomizer is mounted on parallel runners, similar to sled runners, which are fastened to the horizontal supporting feet 84. The atomizer is then slowly pulled along the aisle of the car, so that the atomizing nozzles project the liquid insecticide in all directions under the car seats and into the edges and grills of the railroad car. The compressed air is supplied to the atomizer through a flexible hose, which can be used to pull the atomizer along the aisle. For this type of service the atomizer may be provided with additional vertical nozzles which direct the insecticide fog into the upper strata of the car, thereby penetrating the air-cooling system where vermin may be nesting.

I preferably employ air pressures ranging anywhere from 50 to 100 pounds per square inch in each of the above described embodiments of the invention.

While I have illustrated and described what I

regard to be the preferred embodiments of my invention, nevertheless, it will be understood that they are merely exemplary and that numerous modifications and rearrangements may be made therein without departing from the invention.

I claim:

1. In an insecticide atomizer, the combination of a liquid-holding tank for liquid insecticide, said tank consisting of an elongated cylindrical container having a flat top, an air manifold secured on and located above the flat top, said manifold including a plurality of air jets extending from its opposite sides, a liquid siphon tube for each jet extending through the flat top of the tank and entering into the tank, the upper end of each tube being positioned adjacent to one of the jets and above the flat top, an air-supply pipe located above and extending substantially parallel to the air manifold and coupled to one end of said manifold, a liquid-supply pipe located above the air-supply pipe and extending substantially parallel thereto, said liquid supply pipe being coupled to the tank, float-controlled valve means associated with said tank for automatically maintaining a substantially constant liquid level therein, hangers coupling together the air manifold and the air and liquid-supply pipes, and supporting means at the bottom of the tank on which the tank can be rested and on which said tanks and the pipes coupled thereto can be moved as a unit.
2. In an insecticide atomizer, the combination of a liquid-holding tank for liquid insecticide, the tank consisting of an elongated container, an air manifold secured on and located above the top of the container, said manifold being provided with air jet nozzles, siphon tubes for the air jet nozzles entering the tank and having upper ends located adjacent to the air jet nozzles, an air supply pipe located above the tank and above the manifold, one end of the manifold being connected into said pipe, a suspension hanger connected to the other end of the manifold and having a part embracing the air-supply pipe, a fluid supply pipe arranged parallel to the air-supply pipe, the fluid supply pipe being connected to one end of the tank, the suspension hanger having a part embracing the fluid supply pipe and maintaining it in spaced and parallel relation to the air pipe, and a second suspension hanger extending between the air and fluid supply pipes and holding the same in spaced and parallel relation.
